UNITED STATES PATENT OFFICE.

CLIVE W. LANPHERE, OF NEW YORK, N. Y.

UNIVERSAL JIMMYPFOOF ARC-BOLT LOCK.

Application filed October 30, 1923. Serial No. 671,820.

To all whom it may concern:

Be it known that I, CLIVE W. LANPHERE, a citizen of the United States, and a resident of 635 West 169th Street, New York city, in the county of New York and State of New York, have invented a new and useful Improvement in Universal Jimmy-proof Arc-Bolt Locks, of which the following is a specification.

10 This invention relates to improvements in locks, and more particularly to an automatic lock having an arcuate bolt adapted to be projected into locking engagement with a keeper when a door is closed.

15 An object of my invention is to provide an automatic lock which is dependable in operation, simple in construction and of sufficient strength to resist damage by a jimmy or otherwise.

20 Another object of my invention is to provide a bolt which when projected, will serve to secure a door from movement in any direction away from a jamb.

25 Another object of my invention is to provide an automatic lock of the arcuate bolt type which may be locked in its projected position at such time when the bolt is fully projected.

30 Another object of my invention is to provide an automatic lock of the arcuate bolt type with automatic means adapted to engage the bolt when the latter is fully projected and controlled by the movements of the bolt.

35 A further object of my invention is to provide an automatic lock of the arcuate bolt type in which the latter is automatically locked in its projected and retracted positions (only at such times when the bolt

40 is fully projected or retracted).

45 A further object of my invention is to provide an automatic lock of the arcuate bolt type having a bolt-tumbler which is actuated partly through the action of the

50 A further object of my invention is to provide an automatic lock of the arcuate bolt type which is arranged so as to provide a rigid connection with a guard or keeper.

55 A further object of my invention is to provide an automatic lock having a face plate.

A further object of my invention is to provide an automatic lock of the arcuate bolt type which is capable of manual actuation to project or to retract the bolt and

which may be actuated automatically at the will of the user.

A further object is to provide an automatic lock of the arcuate bolt type which is capable of operation regardless of the displacement of the coacting keeper under normal conditions of shrinkage, etc.

A further object of the invention is to provide an automatic lock of the arcuate bolt type having a co-axial lock barrel and pivotal support for the bolt.

Other objects of the invention will appear as the description proceeds.

Many efforts have been made to produce a satisfactory automatic lock employing an arcuate bolt which is capable of operation under ordinary conditions prevailing in the customary usage to which such a lock is subjected. So far as I am aware, no satisfactory lock of this type which combines 75 simplicity of construction and certainty of operation has been produced.

In the present invention a lock possessing the desired characteristics has been obtained. This lock briefly stated comprises an arcuate bolt which is mounted on a radius arm pivotally supported within the casing housing the locking mechanism. Axially aligned with the pivotal axis of the 80 radius arm is the key or lock barrel. Means are provided within the lock casing for engaging the bolt to hold the same in its projected position thus preventing the lock from being forced by a jimmy or otherwise. Owing to the pivotal mounting of the bolt and the projection of the bolt beyond the supporting radius member, a rigid connection with the keeper is secured, thus rendering the lock more resistant to force 85 applied in the manner above indicated.

In addition to the foregoing desirable features, the lock embodies means for releasing the locking means for engagement with the bolt at such time when the bolt is 100 fully projected, thus avoiding any interference of the bolt with the locking means.

Another feature of the invention is the provision of means for holding the bolt in its retracted position, such means being 105 automatically released when the door is closed and operating to hold the bolt retracted only when the bolt is fully retracted and the door opened. The lock also embodies a construction which enables the releasing means to be rendered ineffective and means are also provided to permit a manual 110

retraction or projection of the bolt when such manual action is required.

Furthermore, the lock is provided with a latch whereby the door to which the lock 5 may be fastened may be secured without employment of the lock.

The bolt employed in the lock forming the subject of my invention is of unique design, one of the purposes of such design being to 10 prevent bending of the lock upon accidental projection thereof before the door is fully closed in the event that the bolt strikes against the jamb. The automatic feature of the lock combined with the various details 15 outlined above, provides a lock meeting the most rigid requirements, either of the type shown or a lock of any other character.

The invention will be more fully understood by reference to the drawings in 20 which—

Fig. 1 is a plan view of a lock embodying the present invention with the bolt projected, the cover plate having been removed and the face plate and keeper being shown 25 in section,

Fig. 2 is a view taken on line II—II in Fig. 1 and shows the face plate of the lock and the projected bolt in section,

Fig. 3 is a transverse sectional view taken 30 on line III—III in Fig. 1,

Fig. 4 is a plan view of the lock with the cover plate removed, the bolt being shown in a retracted position,

Fig. 5 is a vertical section taken on line 35 V—V in Fig. 4, the lock barrel being shown in full lines,

Fig. 6 is a transverse section taken on lines VI—VI in Fig. 4,

Fig. 7 is a sectional view taken on lines 40 VII—VII in Fig. 4, and

Fig. 8 is a fragmentary view of the lock showing a modified form of mechanism for holding the bolt in a retracted position.

The present invention is shown as comprising a casing 15 for the lock-operating mechanism. The casing may be provided 45 with tapped holes 16 to receive screws 17 for the purpose of securing a plate 18 as a closure for the casing. Movable within 50 the casing is an arcuate member or bolt, designated as a whole by the numeral 19, adapted to be oscillated so as to move a tongue portion 21 thereof out from and into 55 the casing. The bolt proper may comprise the said tongue 21, a tail-piece 22 and a stem 23, which latter may be removably connected by a pin 21' to the tongue. These 60 parts may be integral with a radius arm 24, which may be integral with a hub 25 rotatably mounted on a bearing 27 provided in a wall 28 of the casing 15. Disposed centrally 65 within the hub 25 is a stud shaft 26 having a collar 20 secured thereto, which prevents movement of the hub 25 from its bearing within the casing. The collar 20 has a lever

arm 29 secured thereto by means of screws, the function of said arm being described hereinafter. The stud shaft has a flange 76 either integral therewith or sweated thereon which fits into a correspondingly formed 70 depression 76' in the casing wall 28. The function of the flange 76 is to prevent inward movement of the stud shaft.

As illustrated in Fig. 5, the sides of the lock casing are so disposed with respect to 75 the bolt so as to prevent lateral movement thereof, and therefore provide a raceway for the bolt. The bolt is so disposed with respect to the sides of the casing so as to provide a lateral clearance therebetween (see 80 Figs. 3 and 5).

The novel form of my bolt simplifies the construction of the lock and the radial arm or web 24 is utilized to perform certain 85 important functions to be hereinafter more fully described.

The bolt 19 may be projected either manually or automatically and for automatic projection is provided with a helical spring 31 disposed upon the stem 23, one 90 end of the spring being engaged with a shoulder 32 of the bolt and the other end with a stop 33 which may be integral with the casing 15. When the bolt is in its retracted position, the spring 31 is compressed 95 and tends to project the bolt. It is obvious that the spring may be compressed to a greater or lesser degree depending upon the amount of potential energy necessary to throw the bolt. In addition to the action of 100 the spring, however, the construction of the lock is such, that the action of gravity aids to project the bolt. Although my lock is usually positioned in a door so that gravity may aid in effecting a movement of the bolt, 105 it is to be understood that in cases where the lock is not so positioned, the spring may be made of sufficient strength to project the bolt without the aid of gravity.

Inasmuch as the bolt is normally urged to 110 project from the casing, means are provided for preventing such movement until the bolt is disposed in the proper relation to a keeper or guide 34.

Means for retaining the bolt in a retracted 115 position and for effecting the timed release of the bolt, may comprise a latch 35 suitably positioned on the bolt, a trigger or latch-bar 36 and a detent 37. The detent 37 may constitute one end of a releaser- 120 member 38.

The latch-bar 36 may be slidably disposed between one side 39 of the casing 15 and a guide 41 and may have an extended portion 42 provided with a rod 43 disposed in a slot 44 in a rigid projection 45 integral with the side 39 of the casing. A spring 46 positioned on the rod 43 and between a collar 47 and the projection 45, serves to normally maintain the latch-bar with a stop- 130

finger 48 thereof in the path of movement of the detent 37. The releaser-member 38 is provided with a spring 49 disposed between

5 a beveled end portion 50 and a slotted guide 51 fastened to the casing. The detent 37 is therefore normally urged toward the stop-finger 48 or to position for engagement with the latch 35 on the bolt. However, by reason of the spring 46 on the latch-bar 36, the stop-finger 48 is normally positioned to engage with an off-set portion 52 of the detent 37. The detent cannot, therefore, engage with the latch-bar until the stop-finger 48 is moved. A removal of the 10 stop-finger is caused by an engagement between the shoulder 32 on the bolt and the projection 42 of the trigger or latch-bar 36 when the bolt is retracted.

The coordination and arrangement of the several operating parts is such that at the time the bolt is in its final retracted position the trigger releases the detent 37 which moves under the action of the spring 49 to engagement with the latch 35 and thus 15 detains the tongue 21 of the bolt 19 within the casing.

When the detent 37 is moved to release the bolt 19, the potential energy of the spring 31 is released and the bolt travels 20 through a circular path, the tongue thereof passing in one direction through upper apertures 54 and 54' in the side 53 of the casing and the guard 34, respectively, and in another direction through lower apertures 35 55 and 55' in the side 53 and in the guard 34, respectively. The end of the nose piece 56 of the bolt may enter the casing a predetermined distance. The side 53 may include a face plate 53' secured to the casing 25 by flat-headed countersunk screws 50'. The upper opening 54 in the side 53 of the casing may be slotted so as to permit the ready assembly of the bolt within the casing.

It will be understood that by reason of the passage of the bolt-tongue into and out from the apertures, in the guard and casing, that a portion 57 of the guard between the apertures may be so disposed as to prevent a movement of the lock-casing away from 30 the guard and consequently the jamb upon which the guard is fastened. It will thus be evident when a door is secured by the present lock, the bolt is not only secured from pivotal movement, but is also substantially proof against the action of a wedge or jimmy. The guard 34 may be provided with a reinforcing rib 34' which may be welded or otherwise secured to the plate 34.

It has been found of great advantage not 35 only to normally secure the bolt 19 from movement when in its retracted position as hereinbefore described, but to lock the bolt in its projected position. For the latter purpose, the end or nose piece 56 of the tongue 21 is provided with a notch 58 so

disposed as to receive an end 59 of a bolt-tumbler 61 when the bolt is in its projected position.

In the present invention, the bolt-tumbler 61 is provided with a rod 62 (see Fig. 4) 70 having a helical spring 63 mounted thereon. The rod may be disposed in a guide 64 and the spring may engage with a seat 65 on the tumbler and with the guide to normally urge the bolt-tumbler to a position to interlock with the bolt. The bolt-tumbler may be slidable between a wall 53 of the casing and guide lug 67. Means for lifting the bolt-tumbler from the notch 58 may comprise the lever arm 29 secured to the shaft 80 26. The lever 29 may be so positioned that when turned by rotation of the shaft, the lever will engage with an extended portion 68 of the bolt-tumbler 61 and lift the end 59 thereof from the notch 58 and a continued movement of the lever causes it to engage with a stud 69 suitably positioned on the radius arm 24. Thus a rotary movement of the lever effects a movement of the bolt 19 until the same is held by reason of 90 latch 35 and detent 37. In order to prevent unnecessary frictional engagement between the nose piece 56 of the bolt and the end 59 of the bolt-tumbler, the tumbler is provided with a prong 71 adapted to engage 95 with an extended portion 72 of a tumbler-detent 73. The tumbler-detent may be mounted in a guide-bearing 74 which may be integral with the side 53 of the casing and may extend above the radius arm 24 of 100 the bolt 19. A spring 70' positioned between a rigid projection 70 on the guide-bearing and tumbler-detent 73 acts to normally position the extended portion 72 of the tumbler-detent for engagement with the 105 prong 71. When this engagement is effected, the bolt-tumbler is held with the end thereof out of the path of movement of the nose piece 56 of the tongue 21 of the bolt.

A release of the tumbler-detent 73 from 110 engagement with the prong is caused by contact between an exposed end 73' of the tumbler and a pin 74' secured to and projecting from the radius arm 24 which is so positioned, that the release of the bolt-tumbler is 115 timed to enter the notch 58 as the same registers with the end 59 of the tumbler upon the projection of the bolt.

It is desirable to prevent engagement between the end 59 of the bolt-tumbler 61 and 120 an end 23' on the rear or tail-piece 22 of the bolt in order to avoid interference and wear through continued use. Means comprising the tail-piece 22 may, therefore, be provided to engage with a cam arm 75' integral with 125 and projecting from the end 59 of the bolt-tumbler 61. As the bolt 19 is retracted, the tail piece 22 makes contact with the cam arm 75' secured to the bolt-tumbler 61 and the latter is slightly raised thereby to permit the 130

free passage of the end 23' of the rear of the bolt 19 into the aperture 55 in the side 53 of the casing.

The end 23' which is fastened to the rear 5 of the tail piece 22 is also adapted to engage the end of the stem in order to stiffen the support thereof and to prevent any warping through temperature changes, etc.

The end 23' is of sufficient proportions to 10 completely occupy the aperture 55 and must, therefore, have an area substantially equal to a transverse cross-sectional area of the tongue. Although the bolt-tumbler is partially moved by means of the lever 29, as 15 described below, to bring the tumbler out of the path of movement of the end 23' of the stem, it must be lifted higher than the lever 29 moves it, and this may be accomplished by the employment of the cam arm 75' and 20 tail-piece 22.

For the purpose of lifting the bolt-tumbler 61 prior to a movement of the bolt, means are provided whereby the lever 29 may move a predetermined distance prior to engagement 25 with the stud 69. This action is accomplished by a rotation of the lever 29 on the stud-shaft 26 (see Fig. 5) journaled in the bearing 27. The shaft may be retained from 30 endwise movement by the provision of a collar 76 disposed in a counterbore in the casing and the collar or hub 20 of the lever arm 29 secured to an inner end of the shaft.

As above described, the radius-arm 24 is mounted rotatably on the shaft 26 and positioned between the lever 29 and the bearing 27. The shaft may be provided with the usual angular socket 78 in which the shank 79 of a knob may be disposed and by means of which the lever 29 may be operated to retract the bolt. The lever 29 is normally held 40 in engagement with a stop-pin 81 secured to the radius arm 24, through the action of a spring 82 compressibly disposed on a bowed carrier 83 having one end secured in the lever 29 and the other end disposed in a 45 stop-member 85 secured to the radius arm 24. By reason of this construction, the lever 29 is normally urged against the stop-pin 81 and may be moved a predetermined distance 50 without effecting a movement of the bolt 19.

As illustrated in Fig. 1, when the bolt is projected the lever is in position against the stop-pin 81 and in position to be rotated in the direction of the arrow X by a manipulation 55 of the knob-shank 79 which action moves the lever 29 to bring the lever in contact with the bolt-tumbler 61 to lift it from the notch 58 and a further movement of the lever effects a rotation of the radius arm and 60 consequently a retraction of the tongue 21 to position within the casing.

When desirable, the bolt may be secured in a retracted position. For this purpose, I may provide push-buttons 87 and 88 (see 65 Fig. 1). The button 88 may be provided

with a stop-rod 89 shiftable in a guide 91, and may have an end 92 so positioned as to be movable into and out of the path of movement of a lug 93 secured to the radius arm 24. The stop rod 89 may be moved inwardly 70 to engage with the lug by a thrust upon the button 88. An outward movement of the stop-arm may be produced by an inward movement of the button 87 which is associated with the stop-rod 89 by a lever 94 75 movable about a pin 95 secured in the casing 15. The ends of the lever 94 may be positioned in notches 96 and 97 in the stop-rod 89 and the shank of the button 87, respectively. It will be appreciated that the present push 80 button arrangement provides means for directly engaging one of the component parts of the bolt 19. The guide 91 is of sufficient width so as to furnish a support for the sides 85 of the casing, and thus operates as a separator to prevent the sides from being sprung inwardly and interfere with the operation of the lock mechanism.

As described, the lever 29 may be oscillated by a suitable knob or handle from one 90 side of a door, however, a key barrel may be provided to project from the opposite side of the door as shown in Fig. 5. The key barrel may be of any suitable type, the one shown having a cylindrical casing 99 externally threaded and screwed into a tapped hole 101 in the lock casing and may be held in adjusted position by a set-screw, not shown. As illustrated, the key-barrel is eccentrically mounted with respect to the pivotal axis of the arcuate bolt, however, in certain types of locks, for example a rim lock, the key barrel may be concentrically disposed with respect to the pivotal axis of the arcuate bolt. The key-barrel may have 105 the usual tumbler or key cylinder 102 rotatable upon the insertion of a key 103. An arm or ward 104 may be mounted at the inner end of the cylinder 102 and proportioned to engage with an upper end 105 of the 110 stud 69 on the radius arm. Thus when the key is inserted and turned, the arm on the key-barrel will engage with and retract the bolt. The stud or post 69, as stated heretofore, is provided with a shoulder or projection 105, which is in stepped formation to the lower portion of the post. This arrangement permits the key-cylinder to be screwed into the casing without jamming the operating parts of the lock. The arm 104 on the 115 key-cylinder engages the upper step or projection 105, while the arm 29 on the lock-barrel engages the lower portion of the post 69. The bolt may be retracted or projected through either of these instrumentalities. 120

The lever or ward on the key cylinder is so arranged that when the key 103 is turned to rotate the key-barrel, the arm 29 of the knob may remain in its normal position and it will thus be evident that the key and 125 130

- knob-actuating means are independent of each other. The knob and its spindle lever 29 may be employed to project the bolt manually by rotating the knob in a counter-clockwise direction and thus bringing the lever 29 into contact with pin 81, the lever 29 passing under the tumbler arm 68 before the post 74' on the radius arm 24 moves tumbler detent 73 to release the tumbler for 10 engaging the bolt notch 58. If desirable, the bolt may be manually projected by the key-barrel by rotating the latter in a counter-clockwise direction to engage the ward 104 with the other side of the stud 69.
- 15 The present lock may be provided with any suitable form of latch operable independently of the lock mechanism. As shown, this latch may be in the form of a slide-rod 107 having the usual outwardly 20 projecting beveled end 108 and provided with a helical spring 109 positioned between the end 108 and a slotted stop 111 secured to the casing. The inner end of the slide-rod may have an offset arm 112 provided with a 25 lug 113 for cooperation with an arm 114 secured to a rotatable hub 115 journaled in the casing 15. The hub may have an angular socket 116 to receive an end of a knob (not shown) for a manual manipulation of the 30 slide rod. Means for normally maintaining the hub 115 in its operative position may comprise a spring 117 mounted on a bowed member 118 secured to a post 119 fastened to the underside of the arm 114. The casing 35 may be provided with a slotted projection 121 in which the bowed-member is movable and the spring 117 may be positioned between the projection and the post 119. Upon rotation of the hub 115 to retract the latch, 40 the springs 109 and 117 will be placed under compression, and upon release of the knob with which the hub is associated, the spring 109 will return the latch to its projected position and the spring 117 will, independently 45 of the spring 109, return the hub and attached arm 114 to their initial position.
- Although the releaser member and the latch are illustrated and described as independent of each other, it is obvious that 50 these two members may be combined and the releaser bar serve the dual function of releasing the arcuate bolt to permit its projection and also to latch the door in the event the releaser is rendered inoperative.
- 55 When adapting my invention to what is termed a rim-lock construction, I provide a modified form of means for releasing the bolt, and for retaining the same in its retracted position.
- 60 As illustrated in Fig. 8, the radius arm 24 may be provided with a lug 123 positioned to engage with the lip 124 of a stop-member 125. The stop-member may be provided with an integral extended portion 126 having a 65 projection 127 movable in an aperture 128
- in a side 129 of a casing and a spring 131 may be provided to normally bring the lip 124 in the path of the lug 123 as the same is moved with the radius arm when the bolt is retracted. The spring 131 may comprise 70 a helix mounted on a straight portion 132 of the stop member and may be disposed between a shoulder 133 thereof and a slotted guide 134 which may be fastened to the casing. It will be readily seen that when the 75 bolt is retracted it will be automatically secured and may be released by a thrust upon the projection 127 against the guard or any other desirable means. For rendering the releaser means 125, etc., ineffective, a catch 80 123' comprising a headed stud projecting through the side of the casing, may be employed. The stud may be so positioned with respect to the radius arm that it may be projected behind the lug 123 and when thus 85 positioned will render the releasing means ineffective. By merely withdrawing the stud the releasing means may be rendered effective to perform its normal functions. In a 90 rim-lock construction, such as illustrated in Fig. 8, the key-cylinder may be provided with a shank projecting forwardly from the key-plug, which shank may engage a slot in an arm mounted within the casing, the latter, i. e., the arm, being adapted to engage the operating mechanism for the bolt, 95 as illustrated in Fig. 5. Such construction is obvious to those skilled in the art. The modification illustrated in Fig. 8 is more fully illustrated, described, and claimed in 100 my copending application Serial Number 744,327, filed October 18, 1924.
- When my lock and keeper have been mounted in a door and jamb and assuming the bolt has been projected, it may, as above 105 set forth, be retracted either by turning a knob or a key and automatically detained from further actuation. This detention is effected by an engagement between the shoulder 32 on the bolt and the trigger or 110 latch-bar 36. The shoulder and trigger cooperate to effect the engagement of the latch when it has been properly positioned to receive the end of the detent 37 of the releaser or detainer member 38, at which time the 115 nose of the tongue 21 will be positioned substantially flush with the aperture 54 and the end 23' of the tail piece 22 will serve as a closure for the aperture 55 when the bolt is retracted. It will be noted that when my 120 bolt is in a retracted position the face plate presents a comparatively smooth and pleasing appearance. When the bolt 19 is in its retracted position, the bolt-tumbler 61 is held inoperative by reason of its engagement with the tumbler detent and the engagement between the cam arm and the tail-piece.
- The detent 37 having secured the bolt 125 from movement, the door may be automati- 130

cally locked when swung closed at which time the releaser 38 engages with the guard 34 and actuates the detent 37 causing a movement thereof to release the latch 35.

6 The potential energy of the spring 31 is free to act and the bolt enters the guard and encircles the portion 57 therof.

As the bolt travels toward the guard, the tail-piece remains in contact with the cam-
10 arm until the end 21' has passed the end of the bolt-tumbler as the tail-piece clears the arm the bolt-tumbler is retained from movement because of the engagement between the prong thereon and the tumbler 70
15 detent. As the radius arm 24 moves with the bolt the pin 74' on said arm makes contact with the tumbler detent as the notch 58 registers with the end 59 of the bolt-tumbler and affects the interlocking of the bolt and 75
20 bolt-tumbler in the proper timed relation.

One of the features of my invention which makes the lock useful under varying conditions, is the construction of the releaser bar and the detent connected thereto. The 25 relationship between the detent and releaser bar is such that a complete release of the bolt is effected regardless of whether or not the door and jamb be very close to each other. The extent of movement of the releaser bar after the detent has disengaged the bolt is such as to provide in effect a lost motion movement, the releaser bar moving a greater or less distance depending entirely upon the gap existing between the door and 30
35 the jamb.

The term lock barrel as employed in the appended claims may be construed as covering any kind of a spindle or other mechanism for operating the lock mechanism, and 40 in the present embodiment of applicant's invention comprises the spindle 26 and co-operating elements.

Although a preferred embodiment of my invention has been shown and described 45 herein, it is obvious that many modifications may be made therein without departing from the spirit and scope of the invention as set forth in the appended claims.

What is claimed is:—

50 1. A lock comprising a casing, an arcuate bolt having a tongue portion adapted to be projected from said casing, a radius arm pivotally mounted within said casing and engaging said bolt and being transversely offset with respect thereto, and means for automatically projecting said bolt.

2. A lock comprising a casing, an arcuate bolt having a tongue portion of substantially the same thickness as the casing formed 60 by its two main walls adapted to be projected from said casing, a radius arm pivotally mounted within said casing and engaging said bolt behind said tongue, said bolt being transversely offset with respect to 65 said radius arm, and bolt actuating means

disposed within the path of movement of said bolt.

3. A lock comprising a casing, an arcuate bolt having a tongue portion of substantially the same thickness as the casing 70 formed by the two main walls and adapted to be projected from said casing, a radius arm pivotally mounted within said casing and engaging said bolt behind said tongue, said bolt being transversely offset with respect to 75 said radius arm, and a key cylinder lock to actuate said bolt.

4. A lock comprising a casing, an arcuate bolt adapted to be projected from said casing, a radius arm pivotally mounted within 80 said casing and connected with said bolt, means for projecting said bolt, means for locking said bolt in its projected position, and means associated with said radius arm for actuating the said locking means.

5. A lock comprising a casing, an arcuate bolt adapted to be projected from said casing, a radius arm pivotally mounted within 85 said casing and associated with said bolt, means for operating said arm to project 90 said bolt, means for locking said bolt in its projected position, and means mounted on said arm for permitting said locking means to become operative to lock said bolt.

6. A lock comprising a casing, an arcuate bolt adapted to be projected from said casing, means for projecting said bolt, means for locking said bolt in its projected position, means for retracting said locking 95 means, and means for locking said locking means in its retracted position.

7. A lock comprising a casing, an arcuate bolt adapted to be projected from said casing, an oscillatory arm mounted within said casing and associated with said bolt, means for projecting said bolt, means for locking said bolt in its projected position, means for releasing said locking means, retainer means for holding said locking means in released position, and means on said radius arm for 105 controlling the movements of said retainer means.

8. A lock comprising a casing, an arcuate bolt movable from said casing, a radius arm pivotally mounted within said casing and 110 supporting said bolt, means for projecting said bolt, means for retracting said bolt, means for locking said bolt in its projected position, means for locking said bolt in its retracted position, and means on said radius arm for controlling the movements of each 115 of said locking means.

9. A lock comprising a casing, an arcuate bolt adapted to be projected from said casing, a radius arm pivotally mounted on 120 said casing and supporting said bolt, means for projecting said bolt, means for retracting said bolt, means for locking said bolt in its projected position, means for locking 125 said bolt in its retracted position, and means 130

for holding said third-mentioned means inoperative until said bolt is fully projected.

10. A lock comprising a casing, an arcuate bolt adapted to be projected from said casing; a radius arm pivotally mounted within said casing and associated with said bolt, means for projecting said bolt, means for retracting said bolt, means for locking said bolt in its projected position, means for locking said bolt in its retracted position, means for holding said third-mentioned means inoperative until said bolt is fully projected, said fifth-mentioned means cooperating with said radius arm to effect release of said third-mentioned means.

11. A lock comprising a casing, an arcuate bolt adapted to be projected from said casing, a radius arm pivotally mounted within said casing and carrying said bolt, means for projecting said bolt, means for retracting said bolt, means for locking said bolt in its projected position, means for locking said bolt in its retracted position, means for releasing said third-mentioned means, means for releasing said fourth-mentioned means, said releasing means being controlled by movements of said radius arm.

12. A lock comprising a casing having spaced apart openings in one wall thereof, an arcuate bolt with an arc stem and spring adjusted thereto, said bolt when in projected position being disposed in said openings, and having its front and rear ends similarly shaped so as to close said openings when in the retracted position.

13. A lock comprising a casing, an arcuate bolt pivotally mounted on said casing, means for projecting said bolt from said casing, means for retracting said bolt, said retracting means having a common axis with said bolt.

14. A lock comprising a casing, a bolt pivotally mounted within said casing, a spindle to actuate said bolt, said spindle having a flange to hold the bolt in operative position.

15. In a lock, a casing, an arc-shaped bolt pivotally mounted within said casing and having an arc stem and spring adjusted to said stem to project said bolt from said casing.

16. A lock comprising a casing, an arc-shaped bolt having a flaring radius arm pivotally mounted within said casing, and means for retracting said bolt, means on said radius arm cooperating with said first mentioned means to effect the retraction of said bolt.

17. A lock comprising a casing, an arc-shaped bolt having a radius arm pivotally mounted within said casing, and means to hold said bolt within said casing, said means being controlled by said radius arm.

18. A lock comprising a casing having

openings in its face, an arc-shaped bolt having its front and rear ends similarly shaped and adapted to close said openings when said bolt is in its retracted position and means to automatically project said bolt, said bolt when fully projected engaging said openings.

19. A lock having a pivotally mounted arc-shaped bolt consisting of a bolt portion, a tail portion and a stem for a spring overlying said tail portion.

20. A lock having an arc-shaped bolt consisting of a bolt portion, a tail piece, a stem for a spring, and a pivotally supported radius arm for supporting said bolt.

21. A lock comprising a casing, an arcuate bolt pivotally mounted on said casing, means engaging said bolt directly to retract the same, means for projecting said bolt, means operative when said bolt is fully projected to lock the same in its projected position, means for retracting said locking means, and means for holding said locking means retracted until said bolt is fully projected.

22. A lock comprising a casing, a radius arm pivotally mounted on said casing, said radius arm having a forwardly projecting bolt and two rearwardly projecting members one of which is adapted to accommodate a spring for projecting said bolt and the other of which is adapted to engage means for holding said bolt in its retracted position.

23. A lock having an arc-bolt, means for projecting said bolt, a bolt-tumbler adapted to engage said bolt to hold the same in projected position, a detent associated with said tumbler to hold the same in inoperative position, and means for operating said detent to release said tumbler.

24. A lock having a slidable pivotally mounted arc-shaped bolt, a slidable bolt tumbler and a detent cooperating with said tumbler.

25. A lock comprising a casing, an arcuate bolt pivotally mounted within said casing, means for projecting said bolt, means for retracting said bolt, and means for returning said retracting means to its initial position including an arcuate stem and a spring fitted thereto.

26. A lock comprising a casing, an arcuate bolt pivotally mounted within said casing, a guard, said guard having a pair of openings in spaced relation for the entrance of said bolt, said openings being of such size as to permit said bolt to pass therethrough regardless of the usual changes of position of the member to which said casing is attached or with which said lock cooperates.

27. The combination of a guard and a lock comprising a casing, an arcuate bolt pivotally mounted within said casing, means

for projecting said bolt and means for reTRACTING said bolt, means for holding said bolt in its reTRACTed position, releaser means for said bolt, and means independent of 5 said releaser means for rendering the latter ineffective.

28. A lock comprising a casing, an arcuate bolt adapted to be projected from said casing and when projected engaging said 10 casing in a plurality of points, said bolt comprising two end portions adapted to serve as closures for the openings in said casing through which the bolt passes when projected, said end portions being connected 15 by an intermediate section offset with respect to said end portions.

29. In a lock, a casing, an arc-bolt, means for pivotally supporting said bolt, means to project said bolt, means to retract said bolt, 20 means directly engaging said bolt to hold the same reTRACTed and which is adapted to release said bolt, and means to render ineffective said releasing means.

30. A lock comprising a casing, a radius 25 arm pivotally mounted within said casing, an arcuate bolt projecting forwardly from said arm, means for projecting said bolt, means for engaging said bolt when fully projected to hold the same in such position, 30 said means being rendered operative by movement of said radius arm when said bolt is being projected.

31. A lock having an arcuate bolt and a 35 detachable stem secured thereto, said stem being supported at both ends by said bolt.

32. A lock having an arcuate bolt, means for projecting said bolt both manually and automatically, said manual means being disposed within the path of movement of said 40 bolt.

33. A lock having an arcuate bolt, a radius arm pivotally supporting said bolt, means for automatically projecting said bolt, and means for reTRACTing said bolt, said last mentioned means engaging said arm to project 45 said bolt by manual manipulation.

34. A lock comprising a casing, an arcuate bolt, a radius arm pivotally journaled on said casing and supporting said bolt, and 50 means axially aligned with the pivotal point of said arm and cooperating directly with the intermediate portion of said arm to reTRACT said bolt when moved in one direction and to project said bolt when moved 55 in the opposite direction.

35. A lock comprising a casing, a radius arm pivotally mounted on said casing, a spindle centrally disposed with respect to the pivotal point of said radius arm, an 60 arcuate bolt supported by said radius arm, and means on said spindle cooperating with said arm for reTRACTing said bolt.

36. A lock comprising a casing, an arcuate bolt adapted to be projected from said 65 casing, means for projecting said bolt, means

for rendering said projecting means ineffecti- 70 ve, and a latch for engaging a guard when said bolt is rendered ineffecti- 75 ve.

37. A lock comprising a casing, an arcuate bolt adapted to be projected from said 70 casing, means for automatically projecting said bolt, means for locking said bolt in its projected position, means for releasing said locking means, means for reTRACTing said bolt, and means for preventing interference 75 between said locking means and said bolt while the latter is being reTRACTed.

38. A lock comprising a casing, an arcuate bolt mounted on said casing, means for projecting said bolt, means for reTRACTing 80 said bolt, means for locking said bolt in its projected position, and means for first releasing said locking means and then for imparting further movement to the locking means until said bolt is fully withdrawn. 85

39. In a lock, a casing, a pivoted bolt mounted on said casing, a spindle in said casing and disposed axially with respect to the pivotal point of said bolt, and an arm connecting said spindle and said bolt, said 90 bolt being movable by means of said arm.

40. A lock comprising a casing, an arcuate bolt pivotally mounted within said casing, and an arcuate spring to project said 95 bolt. 95

41. A lock comprising a casing, a bearing in the wall of said casing, a pivotal arc-bolt mounted on and supported by said bearing, means to project said bolt, means to hold said bolt projected, and a spindle having an arm directly connecting the same with said bolt to release said holding means and to move said bolt. 100

42. A lock comprising a casing, an arcuate bolt pivotally mounted within said casing, said bolt having a stem, a spring mounted on said stem for projecting said bolt, and means for holding said bolt in its projected position. 105

43. A lock comprising a casing, an arcuate bolt pivotally mounted within said casing, said bolt having a stem, a spring mounted on said stem for projecting said bolt, means for holding said bolt in its projected position, and means for controlling said holding 110 means. 115

44. A lock comprising a casing, an arcuate bolt having front and rear ends, said casing having openings therein through which a portion of said bolt is adapted to pass, said ends serving as closures for said openings, and automatic means for projecting said bolt. 120

45. A lock comprising a casing, an arcuate bolt pivotally journaled on said casing, a lock barrel positioned within the path of movement of said bolt and associated therewith to actuate the same. 125

46. A lock comprising a casing, a spindle mounted for rotary movement within said 130

casing, an arcuate stem secured to said spindle, and a spring mounted on said stem for actuating said spindle in one direction.

47. A lock comprising a casing, a lock barrel supported by said casing, an arcuate stem associated with said lock barrel, and a spring mounted on said stem for rotating said lock barrel.

48. A lock comprising a casing, an arcuate bolt having a pivotal bearing in said casing, a lock barrel mounted within said pivotal bearing, said lock barrel having an arcuate stem and a spring on said stem.

49. A lock comprising a casing, an arcuate bolt supported for movement in said casing, a lock barrel rotatably supported by said casing, a post projecting from said bolt and an arm projecting from said lock barrel adapted to coact with said post to retract 20 and to project said bolt.

50. A lock comprising a casing, an arcuate bolt pivotally mounted within said casing, said bolt having an arcuate spring associated therewith for projecting the same, and a key cylinder supported by said casing and coacting with said bolt for retracting the same.

51. A lock comprising a casing, an arcuate bolt pivotally mounted within said casing, said bolt having a stem and a spring adjusted thereto, and a key cylinder associated with said bolt for retracting the same.

52. A lock comprising a casing, an arcuate bolt pivotally mounted within said casing, an arcuate coiled spring for projecting said 35 bolt, and means to retract said bolt.

53. A lock comprising a casing, an arcuate bolt pivotally mounted within said casing, said bolt having a stem, a spring mounted on said stem and adapted to project said 40 bolt, and means to retract said bolt.

54. A lock comprising a casing, an arcuate bolt pivotally mounted within said casing, said bolt having a stem, a spring mounted on said stem and adapted to automatically project said bolt, and means to hold the bolt inoperative.

55. A lock comprising a casing, an arcuate bolt pivotally mounted within said casing, said bolt having a projecting tongue and a 50 stem, a spring mounted on said stem, and means to hold said bolt retracted.

56. A lock comprising a casing, an arcuate bolt pivotally supported by said casing, a lock barrel concentrically mounted with respect to said arcuate bolt and coacting therewith to retract said bolt, and a cylinder lock eccentrically mounted with respect to said arcuate bolt and having a key barrel concentrically mounted with respect to said bolt 60 and coacting therewith to retract the same.

57. A lock comprising a casing, an arcuate bolt pivotally mounted within said casing, means for projecting said bolt, a latch, means for retracting said latch, means for projecting said latch, and means for return-

ing said retracting means to initial position.

58. A lock comprising a casing, an arcuate bolt pivotally mounted within said casing, said casing having a pair of openings in one 70 face thereof through which said bolt is adapted to be projected, one of said openings being in the form of a slot whereby said bolt may be readily assembled within said casing.

59. A lock having a latch, means for retracting said latch, an arcuate stem secured to said means, and a spring mounted on said stem.

60. A lock comprising a casing, an arcuate bolt pivotally supported by said casing, 80 means for projecting said bolt, means for retracting said bolt, means for holding said bolt retracted, and releaser means for releasing said bolt, and a latch.

61. A lock comprising a casing, an arcuate bolt pivotally mounted within said casing, means for projecting said bolt, means for retracting said bolt, means for holding said bolt retracted, and means for releasing said last-mentioned means, means for rendering 90 said releasing means, ineffective, and a latch.

62. A lock comprising a casing, a pivotally mounted bolt movable in a curved path, a stem associated with said bolt, a resilient member compressible by a movement of said bolt in one direction and means for automatically releasing said member to move the bolt in another direction.

63. In a lock, the combination of a casing, a pivotally mounted arcuate bolt, a helical spring, a stem associated with said bolt and movable within said spring, means for holding said spring compressed, and means for automatically releasing said spring to 100 move said bolt.

64. In a lock, the combination of a pivotally mounted bolt comprising a tongue and a stem, a helical spring mounted upon said stem, means for moving said stem within said spring to accumulate energy, and means for automatically releasing said energy to actuate said bolt.

65. In a lock, the combination of a bolt comprising a tongue and a stem, a helical 115 spring, mounted upon said stem, said bolt having a tail piece and an end piece, the latter being secured to the tail piece and engaging said stem to support the same in part.

66. A lock comprising a casing, a bolt pivotally mounted, means for projecting said bolt, means for locking said bolt in its projected position, and means controlling the movement of said last-mentioned means at 125 such time when the bolt is fully projected.

67. A lock comprising an arc-bolt mounted within the lock casing, and a key-cylinder screwed in said casing and cooperating with said bolt.

68. A lock comprising a casing, an arc-bolt adapted to be projected from said casing, means for projecting said bolt, means for locking said bolt in its projected position, means for retracting said locking means, and means for locking said locking means in its retracted position.
69. A lock comprising a casing, a radius arm pivotally mounted within said casing, a curved bolt projecting forwardly therefrom, said bolt being offset transversely with respect to said radius arm, and means for actuating said bolt, said means being disposed within the path of movement of said bolt and engaging said radius arm.
70. An arc bolt lock comprising a pivotally mounted arc-bolt, means to project said bolt, means to retract said bolt, common means to hold said bolt retracted and to release the same for projection, and means to render said common means ineffective.
71. A lock comprising a lock casing, a radius arm pivotally mounted within said casing, an arcuate bolt supported by said arm, a lock-barrel, a key cylinder, a stepped post mounted on said radius arm, one step of said post cooperating with said lock barrel and the other step of said post cooperating with said key cylinder.
72. A lock comprising a casing, a pivotal bolt adapted to be projected from said casing, said bolt when projected engaging the casing at a plurality of points, and resilient means directly cooperating with said bolt for projecting the same.
73. A lock comprising a casing, an arcuate bolt adapted to be projected through one face of said casing, a pair of spaced apart openings in said face through which said bolt is adapted to be projected, one of said openings being in the form of a slot, and a cover face plate for said casing having openings in alignment with the openings in the face of said casing.
74. A lock comprising a casing, a radius arm rotatably mounted on said casing, a spindle centrally disposed within said radius arm, an arcuate bolt supported by said radius arm, and means on said spindle cooperating with said arm for retracting said bolt.
75. A lock comprising a casing, a bolt mounted for movement within said casing, a raceway recess in said casing for said bolt, said bolt being movable in said raceway recess with sufficient clearance to permit easy movement thereof.
76. A lock comprising a guard, a casing having a bolt member adapted to move out of said casing in a curved path to engage the guard, and a latch disposed outside of the path described by the movement of said bolt member and adapted to engage said guard, and means to operate said bolt member and said latch.
77. A lock comprising a casing having a plurality of bolt openings, an arc bolt within said casing, said bolt having a forwardly projecting tongue, a radius arm transversely offset with respect to and connected to said bolt, said radius arm being pivotally mounted within said casing, said bolt when projected engaging said casing at said openings and when in retracted position closing said openings, and means within the path of movement of said bolt to operate the same.
78. A lock comprising a casing, an arcuate bolt adapted to have a portion thereof projected from said casing, a guard having spaced openings for the passage of said bolt, a latch disposed outside of the path of movement of said bolt, said latch engaging another opening in said guard, the clearance between said latch and guard opening therefor being of a different order of magnitude than the clearances between the bolt and guard openings therefor.

In testimony whereof, I have hereunto subscribed my name this 22nd day of October, 1923.

CLIVE W. LANPHERE.

68. A lock comprising a casing, an arc-bolt adapted to be projected from said casing, means for projecting said bolt, means for locking said bolt in its projected position, means for retracting said locking means, and means for locking said locking means in its retracted position. 50
69. A lock comprising a casing, a radius arm pivotally mounted within said casing, a curved bolt projecting forwardly therefrom, said bolt being offset transversely with respect to said radius arm, and means for actuating said bolt, said means being disposed within the path of movement of said bolt and engaging said radius arm. 55
70. An arc bolt lock comprising a pivotally mounted arc-bolt, means to project said bolt, means to retract said bolt, common means to hold said bolt retracted and to release the same for projection, and means to render said common means ineffective. 60
71. A lock comprising a lock casing, a radius arm pivotally mounted within said casing, an arcuate bolt supported by said arm, a lock-barrel, a key cylinder, a stepped post mounted on said radius arm, one step of said post cooperating with said lock barrel and the other step of said post cooperating with said key cylinder. 65
72. A lock comprising a casing, a pivotal bolt adapted to be projected from said casing, said bolt when projected engaging the casing at a plurality of points, and resilient means directly cooperating with said bolt for projecting the same. 70
73. A lock comprising a casing, an arcuate bolt adapted to be projected through one face of said casing, a pair of spaced apart openings in said face through which said bolt is adapted to be projected, one of said openings being in the form of a slot, and a cover face plate for said casing having openings in alignment with the openings in the face of said casing. 75
74. A lock comprising a casing, a radius arm rotatably mounted on said casing, a spindle centrally disposed within said radius arm, an arcuate bolt supported by said radius arm, and means on said spindle cooperating with said arm for retracting said bolt. 80
75. A lock comprising a casing, a bolt mounted for movement within said casing, a raceway recess in said casing for said bolt, said bolt being movable in said raceway recess with sufficient clearance to permit easy movement thereof. 85
76. A lock comprising a guard, a casing having a bolt member adapted to move out of said casing in a curved path to engage the guard, and a latch disposed outside of the path described by the movement of said bolt member and adapted to engage said guard, and means to operate said bolt member and said latch. 90
77. A lock comprising a casing having a plurality of bolt openings, an arc bolt within said casing, said bolt having a forwardly projecting tongue, a radius arm transversely offset with respect to and connected to said bolt, said radius arm being pivotally mounted within said casing, said bolt when projected engaging said casing at said openings and when in retracted position closing said openings, and means within the path of movement of said bolt to operate the same. 95
78. A lock comprising a casing, an arcuate bolt adapted to have a portion thereof projected from said casing, a guard having spaced openings for the passage of said bolt, a latch disposed outside of the path of movement of said bolt, said latch engaging another opening in said guard, the clearance between said latch and guard opening therefor being of a different order of magnitude than the clearances between the bolt and guard openings therefor. 100
- In testimony whereof, I have hereunto subscribed my name this 22nd day of October, 1923. 90

CLIVE W. LANPHERE.

DISCLAIMER.

1,525,303.—*Clive W. Lanphere, New York, N. Y. UNIVERSAL JIMMYPROOF ARC BOLT LOCK.* Patent dated February 3, 1925. Disclaimer filed October 18, 1927, by the patentee:

Hereby enters this disclaimer to those claims in said specification which are in the following words, to wit:

“9. A lock comprising a casing, an arcuate bolt adapted to be projected from said casing, a radius arm pivotally mounted on said casing and supporting said bolt, means for projecting said bolt, means for retracting said bolt, means for locking said bolt in its projected position, means for locking said bolt in its retracted position, and means for holding said third-mentioned means inoperative until said bolt is fully projected.”

“66. A lock comprising a casing, a bolt pivotally mounted, means for projecting said bolt, means for locking said bolt in its projected position, and means controlling the movement of said last-mentioned means at such time when the bolt is fully projected.”

“72. A lock comprising a casing, a pivotal bolt adapted to be projected from said casing, said bolt when projected engaging the casing at a plurality of points, and resilient means directly cooperating with said bolt for projecting the same.”

[Official Gazette November 8, 1927.]
